Attorney

UNITED STATES PATENT OFFICE

BENJAMIN P. DILLARD, OF GEEER, SOUTH CAROLINA

COTTON GIN FEEDER

Application filed February 19, 1932. Serial No. 594,076.

My invention relates to cotton gins, and has particular reference to automatic means for regulating the feed of the cotton to the roll box.

An important object of my invention is to provide means to automatically regulate the feed of cotton to the roll box, which means is controlled by the accumulation of cotton upon the roll within the roll box.

A further object of the invention is to provide means of the above-mentioned character, which is adjustable to operate under different selected tensions, whereby the cotton will be automatically fed to the roll to maintain the cotton upon the roll at a desired tightness.

Other objects and advantages of the invention will be apparent during the course of the following description.

In the accompanying drawing, forming a part of this specification, in which like numerals are employed to designate corresponding parts throughout the same,

Figure 1 is an end elevation of a gin embodying my invention,

Figure 2 is a fragmentary side elevation of the same,

Figure 3 is a perspective view of the pawl shifting means, and,

Figure 4 is a side elevation, partly diagrammatic, of the float or gin breast.

In the accompanying drawing, wherein for the purpose of illustration is shown a preferred embodiment of my invention, the numeral 5 designates a roll box of a cotton gin, within which is mounted to rotate a roll 6, in operative relation to gin saws 7, as is well known. The means to feed the cotton to the roll box and to the roll 6 embodies a hopper 8, having a pair of transverse shafts 9, extending therethrough, which carry the usual feed rolls, not shown. These shafts are driven in unison, and in opposite directions by gears 10, engaging as shown. One shaft 9 has a ratchet wheel 11, rigidly secured thereto, which serves to drive the shaft 9.

The ratchet wheel 11 is turned by means of upper and lower pawls 12 and 13, which are pivotally mounted upon a vertically swinging lever 14, as shown at 15 and 16. The

lever 14 is supported by a pivot 17, carried by a fixed support 18. During the operation, the lever 14 is continuously oscillated by means of a link 19, having pivotal connection with the lower end of the lever 14, by means of a bolt 20, or the like, adjustable within a longitudinal slot 21, to regulate the throw of the lever 14. The link 19 is pivotally connected with a wheel 22, which is driven by a pulley 23, receiving its rotation from any suitable source. When the pulley 23 is rotated, it is thus seen that the lever 14 is oscillated, and the pawls 12 and 13 will intermittently actuate the ratchet wheel 11, to effect a step by step turning movement of the same.

Controlling means are provided for regulating the action of the pawls 12 and 13, comprising a lever 24, which is pivotally supported at its outer end as shown at 25. This lever has a lifting element 26 rigidly attached to its inner or free end, and this lifting element embodies oppositely facing pockets 27 and 28, receiving pawls 12 and 13, respectively. The pocket 28 is longer than the pocket 27, whereby the end wall of pocket 27 will elevate pawl 12 out of engagement with the ratchet wheel 11, before the end wall of pocket 28 will elevate pawl 13 out of engagement with this ratchet wheel. The lever 24 has pivotal connection between its ends, as shown at 29, with a connecting rod 30, which is longitudinally adjustable by means of a turning buckle 31, or the like. The lower end of this connecting rod is pivotally connected with a tension element or lever extension 32, as shown at 33. This tension element is pivotally supported at its forward end by a fixed pin or pivot 34. At its rear end, the tension element or lever extension 32 has a slotted pivotal connection, as shown at 35, with a lever 36, which is rigidly mounted upon the outer end of a horizontal rock shaft 37. This rock shaft has a float or breast 38 rigidly attached thereto, and extending above the same, to be arranged in close relation to the roll 6, and to engage with the cotton wound upon this roll, and to be moved outwardly by such engagement. This float or breast is preferably provided at its free end with a laterally extending flange 39, for movement into a re-

cess 40, formed in the stationary bar 41. The float or breast 38 is of substantially the same length as the roll 6. Arranged beneath the tension element or lever extension 32 is a retractile coil spring 42, having one end attached to the roll box 5, as shown at 43, while its opposite end is provided with a hook 44, adapted to engage within notches 45, formed upon the tension element 32. By moving the spring 42 from the pivot 34, the downward pull of the tension element 32 is increased, which increased tension is imparted to the float or breast 38. Therefore, the cotton will be wound upon the roll 6 with a greater tightness before such wound cotton will shift the float 38 outwardly, to cut down or stop the feed of cotton to the roll.

The operation of the machine is as follows:

The roll 6 and saws 7 operate in the usual manner, to gin the cotton, and the cotton is fed from the feeding means by the action of the pawls 12 and 13 upon the ratchet wheel 11. The spring 42 being adjusted upon the tension element 32, to the desired point from the pivot 34, the feeding means will continue to feed cotton to the roll box 5, which cotton is wound or accumulates upon the roll 6. When the accumulation of cotton upon the roll 6 reaches a selected thickness, and tightness, such cotton will force the float 38 upwardly and rearwardly. This action swings the forward end of the lever 38 upwardly, swinging the rear or inner end of the tension element 32 upwardly. This upward movement of the tension element 32 raises the rod 30, causing lifting element 26 to first move the upper pawl 12 out of engagement with the ratchet wheel, and the lower pawl 13 may be subsequently moved upwardly out of engagement with the ratchet wheel. The rolls of the feeding means may thus be either reduced in speed or stopped, to regulate the supply of cotton to the roll box. When the thickness and tightness of the cotton upon the roll 6 drops below a selected point, the tension element 32 again moves downwardly, whereby pawls 13 and 12 will engage the ratchet wheel 11, in the order stated, again effecting its turning movement, to supply an additional amount of cotton to the roll box. It is thus seen that the operation of the control means is entirely automatic, and that the tightness of the cotton wound upon the drum 6 within the roll box, may be regulated by adjusting the spring 42 longitudinally upon the tension element 32.

It is to be understood that the form of my invention herewith shown and described is to be taken as the preferred example of the same, and that various changes in the shape, size and arrangement of parts may be resorted to without departing from the spirit of the invention or the scope of the subjoined claims.

Having fully described my invention, what I claim is:

1. The combination with a gin embodying a roll box, a roll therein, of a float disposed upon one side of the roll for movement toward and away from the same and to engage with the cotton upon the roll, a lever connected with the float to be moved thereby, a tension element having one end supported by a fixed pivot and its other end pivotally connected with the lever, a spring having means for engagement with the tension element and to be adjusted longitudinally of the tension element, mechanism for feeding cotton to the roll box, and means to regulate the action of said mechanism, including a part having connection with the tension element. 70

2. The combination with a gin embodying a roll box, and a roll therein, of a float disposed upon one side of the roll and pivotally supported to turn about its longitudinal axis, a lever connected with the float to turn therewith, a tension element having its outer end supported by a fixed pivot and its inner end pivotally connected with said lever, a spring engaging the tension element and adjustable longitudinally of the same, mechanism for feeding cotton to the roll box including a pawl and ratchet, and means to lift the pawl out of engagement with the ratchet, said means being connected with the tension element to be moved thereby. 80

3. The combination with a gin embodying a roll box and roll therein, of a pivoted float arranged near and upon one side of the roll, a lever connected with the float to turn therewith, a tension element having a fixed pivot near its outer end and also pivotally connected with the lever near its inner end, yielding means engaging the tension element at a point between its pivots to swing the inner end of the tension element downwardly, mechanism for feeding cotton to the roll box, and means to regulate the action of said mechanism including a part connected with the tension element at a point between the pivots of the tension element. 100

4. The combination with a gin embodying a roll box and roll therein, of a pivoted float disposed upon one side of the roll, a lever connected with the float to move therewith, a generally horizontal tension element having its outer end supported by a fixed pivot and its inner end pivotally connected with the lever, a retractile coil spring arranged beneath the tension element and having its upper end engaging the tension element and adjustable longitudinally of the same, mechanism for feeding cotton to the roll box including a pawl and ratchet, and means to lift the pawl out of engagement with the ratchet, said means being connected with the tension element to be moved thereby. 115

In testimony whereof, I affix my signature.

BENJAMIN P. DILLARD.
